LINE-UP AND REGISTERING TABLE FOR
PRINTERSJames West, Newton, and William M. Davis,
Cambridge, Mass., assignors to Craftsman Line-
Up Table Corporation, Waltham, Mass., a cor-
poration of Massachusetts

Application November 9, 1939, Serial No. 303,550

18 Claims. (Cl. 33—184.5)

This invention relates to that class of apparatus used in the printing trade and commonly known as "line-up tables." They are utilized primarily for the purpose of securing accurate line-up of the work and precision register of the copy, although useful for other purposes also.

The present invention aims to improve tables of this character with a view to increasing their range of usefulness and facilitating the performance of work connected with the printing industry for which prior constructions have not been adapted. In particular, it aims to devise means whereby the workman can rule plates and negatives with speed and accuracy, can space the rule lines precisely, to make the operations performed on such a table easier for the operator to execute accurately, and to facilitate the use of these tables in ruling negatives, masking, stripping, opaquing, and other operations required in the various types of printing. It also aims to reduce the liability of accidentally injuring some of the parts.

In the accompanying drawings which illustrate a preferred embodiment of the invention,

Figure 1 is a perspective view of the table; Fig. 2 is a plan view with parts broken out; Figs. 3 and 4 are sectional views approximately on the lines 3—3 and 4—4, respectively, Fig. 2;

Figs. 5 and 6 are vertical and horizontal sectional views, respectively, of stops used on the carriages;

Figs. 7 and 8 are sectional and plan views, respectively, of a magnifying sight tube which forms an element of the apparatus;

Fig. 9 is a side elevation showing one end of the horizontal carriage in its elevated position;

Fig. 10 is a sectional view through a portion of the mechanism for raising and lowering the glass top;

Fig. 11 is a rear elevation illustrating the interlocking means between the carriages;

Fig. 12 is a rear elevation of a part of the horizontal carriage showing means for automatically raising the sight tube on the latter carriage to prevent interference with a stop on the vertical carriage;

Fig. 13 is a sectional view approximately on the line 13—13, Fig. 12;

Fig. 13a is a plan view of a stop provided with a cam;

Fig. 14 is a vertical, sectional view through a portion of the spacing mechanism;

Figs. 15 and 16 are plan and end views, respectively, of the spacing mechanism;

Fig. 17 is a side elevation, with parts in sec-

tion, illustrating a lighting apparatus which preferably is used with the transparent table top;

Fig. 18 is a vertical, sectional view approximately on the line 18—18, Fig. 17; and

Fig. 19 is a vertical, sectional view through the frame portion of the table top showing means provided by this invention for use in squaring up the upper section which carries the glass plate.

Referring first to Figs. 1 and 2, the construction there shown comprises a frame 2 and a table top 3, the latter being hinged at its forward edge to the frame so that its rearward edge can be lifted and supported in any convenient manner with the entire top in an inclined position. The table top includes a rectangular metal frame with a central glass plate 4 and surrounding marginal strips 5. Along the front of the opening in which the plate 4 is located, a metal scale 6 is provided, as best shown in Fig. 1. So far as this part of the apparatus is concerned, the construction is similar to tables in common use.

Mounted for movement across this table top in directions at right angles to each other, are two carriages indicated, in general, at 8 and 9, respectively, the former usually being referred to as the "horizontal carriage" and the latter as the "vertical carriage" because they are used in making horizontal or vertical lines, respectively, or in checking alignment in these directions. The latter cooperates with the scale 6 and the former with a similar scale 28 mounted on the carriage 9.

As shown in Figs. 1, 2 and 3, the horizontal carriage comprises a shaft 10 supported by gears 11—11 fixed thereon near opposite ends thereof, these gears running on toothed racks or tracks 12—12 secured to the frame pieces 13 of the table top. The gears are enclosed in housings 14—14, one of them being provided with an integral extension 14', and a truss bar 15, square in vertical section, is secured at one end to said extension and at its opposite end to the gear housing at the right-hand end of the table. A metal straight edge 16', Fig. 2, is secured to the bottom of the bar 15 and is graduated along its margin, the bar lying normally just above the surface of the glass top 4. At the left-hand end of the carriage the shaft 10 is equipped with a hand wheel 16. Consequently, by turning this wheel the carriage may be moved backward or forward on its racks, or it can merely be pushed by hand. Preferably the portion of the shaft 10 between the gear casings is enclosed loosely in a sleeve

18, and a hand piece 17 is secured to it. The carriage may be locked in any position of adjustment by turning down a thumb screw 20 so that its lower end will bear against the shaft 10.

The vertical carriage 9 is similar in construction to the horizontal carriage and includes a shaft 21, Fig. 4, supported on gears 22-22 enclosed in housings 23-23 and running on toothed racks 24-24. A hand wheel 25 is secured to the right-hand end, Fig. 1, of the shaft and, if desired, the portion of the latter between the gear casings may be enclosed loosely in a sleeve 26, as shown in Fig. 4. This carriage also is equipped with a truss bar 27 and a straight edge 28 secured thereto, all of these parts being constructed and arranged in essentially the same manner as the horizontal carriage. Similarly, it includes a set screw 30, Figs. 1 and 2, by means of which the carriage may be locked in any desired position.

These straight edges and their cooperating truss bars are utilized in performing the aligning, marking, registering, and similar functions. For this purpose they must both be movable in a plane closely adjacent to the surface of the glass top 4, and both obviously cannot occupy this position at the same time. One feature of this invention, therefore, resides in an arrangement whereby one carriage can be moved into a plane entirely out of the path of travel of the other whenever it is desired to use the latter. As shown, the tracks or racks 12-12 for the horizontal carriage 8 are provided near their rearward ends with inclined portions *a-a*, Fig. 1, followed by short horizontal lengths *b-b* so that this carriage can be pushed rearwardly on to the elevated parts *b-b* of its track where it will be entirely above the plane of operation of the vertical carriage 9. The latter can then be used without danger of interference with the former.

Normally the vertical carriage 9 is locked in its extreme left-hand position, as shown in Figs. 1 and 2, by means of a spring latch 31, Figs. 1 and 2, which snaps over a stop 32 fast on the frame. In this position the arm 14' of the horizontal carriage clears the vertical carriage parts which overlie the working area of the table, as clearly shown in Fig. 3.

It is also important to lock the horizontal carriage in its elevated and inoperative position. For this purpose a headed stud 33, Figs. 2 and 9, is rigidly secured in the left-hand gear casing 14 for the horizontal carriage and projects rearwardly therefrom where it may be engaged by a spring pressed latch 34, Fig. 11, which is pivoted on the machine frame at 35. So long as the vertical carriage is in its inactive position, as shown in Figs. 1 and 2, it bears against the lower end of the latch and holds it in its dotted line position, as shown in Fig. 11. As soon, however, as the vertical carriage is moved away from its idle position, even by a very small amount, it releases the latch, and the latter then engages the stud 33 and locks the horizontal carriage in its inoperative position. The horizontal carriage remains locked until released by the movement of the vertical carriage back into its idle position again where it is automatically locked by the spring latch 31. Thus this interlocking arrangement prevents interference of one carriage with the other.

Either carriage can be tipped about the axis of its own shaft to raise its straight edge and such tipping movement of the horizontal carriage is limited by a roll 36, Fig. 9, mounted on

a small lever pivoted on the carriage. The normal position of the carriage is determined by a roller 37, Figs. 9 and 11, running on the table top just inside the racks. Any danger of lifting either gear 11 out of mesh with its track is prevented by a pin 38, Fig. 9, both the pin and the roll 36 underlying a flange or rail 49, Fig. 3, which projects laterally beyond the rack. At the raised sections of the tracks a supplemental flange 41, Fig. 9, is provided, this flange being cut away, as shown at 42, to permit the passage of the pin 38. Similar pins and rolls are provided to cooperate with the corresponding elements on the vertical carriage.

The scales 6 and 28 are graduated very accurately and in such closely spaced divisions that it is tiresome and sometimes difficult to use them. In order to avoid this difficulty and to facilitate the precise positioning of the carriages, each is equipped with a magnifying sighting tube. A typical form is shown at 44 in Figs. 7, 8 and 12. On the vertical carriage such a tube is simply mounted on a bracket 45, Fig. 2. On the horizontal carriage, however, the tube is supported on an arm 46 pivoted on the stud 47, Figs. 12 and 13. In either event, the sighting tube is so positioned as to overlie the scale with which its respective carriage cooperates during its entire path of travel. Also, each tube is equipped with a mark or cross-hair adapted to be registered with the graduations on the scale. Such an arrangement facilitates accurate adjustment of the carriages and reduces the fatigue and eye strain required in making adjustments.

In using this machine a ruling pen, scoring implement, or marking device of some kind is mounted on one or the other of the bars 15 or 27. Such a device is shown in Fig. 1 at 48 fitting slidably on the bar. Often it is necessary to move this device repeatedly through a given range of travel in order to make a series of parallel lines of predetermined lengths. For this purpose stops, such as those shown at 50 in Figs. 2, 5 and 6, are adjustably mounted on the bars. There is some tendency for the repeated striking of these stops by the marking device to move the former out of their adjusted positions. According to this invention, therefore, each of the bars 15 and 27 is provided with tapered grooves, such as those shown at 51 in Figs. 5 and 6; and a gib 52 of corresponding cross-sectional shape is carried by each stop and held in the groove by a set screw 53. By tightening up this screw the stop may be locked very securely to the bar.

As will be observed from an inspection of Figs. 2 and 3, the extension 14' of the left-hand gear casing 14 overlies the vertical bar while the horizontal carriage is in its operative position. As it is moved backward and forward, there is danger of the arm 46 which supports the sighting tube 44 striking one of the stops 50 on the vertical carriage. Each of these stops, therefore, preferably is provided with a cam piece 51, Fig. 13, and a pin 52 is secured to the lower side of the arm 46 so that, in the event of engagement with the cam, these two parts 51 and 52 will cooperate to swing the arm 46 into an elevated position where it will ride over the stop.

A limited vertical adjustment of the glass plate 4 is desirable to accommodate work of varying thicknesses. According to this invention, this plate is mounted on blocks 53, Fig. 10, of fiber, or other suitable material, supported in an angle iron frame 54. At its four corners the frame is supported by vertical screw-threaded

studs, one of which is shown in Fig. 10 at 55, the points of the screws fitting into tapered sockets in the upper ends, respectively, of four shafts 56, each having a section screw-threaded through a portion of the stationary frame of the machine. Below the screw-threaded portion a sprocket wheel 57 is secured to each of these shafts. Also, as shown in Fig. 2, a sprocket chain 58 engages all of the sprocket wheels and is attached to a slide 60 provided with a handle 61 which projects at one side of the frame into a convenient position to be grasped by the operator. Thus by moving the slide backward or forward, all of the sprocket wheels and their shafts may be revolved simultaneously, thus threading the shafts up or down, depending upon their direction of rotation, and thereby changing the elevation of the glass plate 4 to suit the requirements of the work in hand.

An important use of a table of this kind involves the drawing of a large number of closely spaced parallel lines as, for example, in ruling negatives. This is a very exacting and laborious operation requiring much skill, patience, and extremely good eyesight. It is one of the objects of this invention, therefore, to reduce the time, labor, and skill involved in performing operations of this kind. To this end the invention proposes to equip one or both of the carriages with a mechanism designed to be operated by a lever, or equivalent device, which will automatically adjust the carriage by a distance predetermined by the operator so that it is merely necessary for him to set the apparatus to the spacing desired and then operate the lever, the adjusting or spacing movement being produced automatically. A further feature of this invention is that the mechanism is made of a double or duplex character so that spacings in predetermined fractions of an inch, or in some measure better suited to the printing trade, such as picas, can be made, as desired, and a shift from one to the other can be accomplished quickly and conveniently.

Considering first the vertical carriage 9, the gear housing 23 at the right-hand end, Fig. 1, of the carriage 9 is replaced by such a housing as that shown at 63 in Figs. 14 to 16, this housing being adapted to receive the shaft 21 and its co-operating gear 22. Meshing with the gear 22 is a split driving pinion comprising two sections 64 and 65, the former being secured to a shaft 66 and the latter to a hollow shaft 67 in which the first shaft fits. At the right-hand end, Fig. 14, the two shafts are connected by a coiled spring 68, better shown in Fig. 16, this connection being made to a small knurled wheel or knob 70 secured to the outer shaft by a set screw 71. The spring 66 exerts a torsional action tending to revolve one shaft relatively to the other and thus, in effect, spreads the teeth of the pinion which drives the gear 22 at any instant and thus prevents any back lash in this driving connection. The composite shaft so provided is supported in ball bearings 72 and 73.

Two ratchet wheels 74 and 75, respectively, Fig. 14, are mounted fast on clutch hubs 76 and 77, respectively, the former rotating freely on the shaft 67 and the latter on a clutch member 78 keyed to said shaft. Another clutch element 80, similar to the part 78, is likewise keyed to the hollow shaft 67. Between these members is a disk 81 mounted on a ball bearing 82 on a hub portion of the part 76, suitable clearance being provided between the parts 76 and 77 to enable the disk 81 to be revolved freely at all times.

The tapered surfaces between the parts 76 and 80 and between the similar parts 77 and 78 adapt them to function as friction clutches and they may be locked in a clutching relationship by turning the collar 83 which is screw-threaded on the shank of the part 70. When so locked the pinion 64-65 is secured rigidly to both ratchet wheels 74 and 75. The latter are provided with teeth of different spacings in order to produce different angular movements of the pinion for the same angular movement of the disk 81, and a lever 84 provided with a handle is secured to said disk in order to operate it. Pivoted on this lever are two pawls 85 and 86 and each has an hexagonal portion rigid therewith, that on the pawl 85 being shown at 87, Fig. 16. A T-shaped spring 88 secured to said lever has its free ends curved to bear, respectively, against the flattened faces of the part 87 for the pawl 85 and also against a corresponding part for the other pawl, so that the spring tends to hold both pawls in engagement with their respective ratchet wheels. However, if either pawl is lifted manually, the spring will snap over on to another flat face and will then hold that pawl in an inoperative position. Thus either pawl and ratchet unit of the spacing mechanism may be used, as desired. The amplitude of swing of the operating lever 84 is limited by a stop screw 90 threaded through a stationary bracket 91, Fig. 16, and by another stop screw 92 secured to a bracket 93 adjustable in a dovetail guideway formed in the sector 94. Its position along said guideway may be changed as desired and it may be locked in its adjusted position by a clamping screw 95. Also, the bracket 93 carries a gauge plate 96, Fig. 15, overlying a graduated plate 97 which is secured to the outer curved surface of the sector 94. The plate 97, as shown, carries two scales, one graduated in, say, sixty-fourths of an inch and the other in picas, or seventy-seconds of an inch. Often, however, the latter graduation is replaced by one in thousands of an inch, in which case the ratchet wheel 74 is replaced by one with a different tooth spacing.

In using this mechanism if the pawl 86 is thrown out of operation, the workman can adjust the slide 93 so that for each stroke of the lever 84 he will move the vertical carriage 9 a certain fraction of an inch. That fraction may be made anything that he wishes within the range of the apparatus. Usually these adjustments are made anywhere from a sixty-fourth of an inch to half an inch. He can repeat a given spacing as frequently as he wishes and change whenever he desires. If he wishes to change to the pica scale, he can do that at any time by throwing out the pawl 85 and swinging the other pawl 86 into its operative position. The clutch arrangement enables him to position his straight edge accurately for the start of the ruling operation and then, by releasing the clutch, to bring a tooth of the selected ratchet wheel into engagement with the pawl so that when the clutch has been tightened up and he makes his first movement of the lever 84, an accurate spacing will be produced. The locking screw 30 for the carriage is inserted in the hole 30', Fig. 15.

With the aid of such a spacing mechanism, the labor involved in ruling forms and plates is greatly reduced and it can be performed easily with a degree of accuracy that is very difficult indeed for a workman to duplicate by hand. Also, by releasing the clutch the carriage can be manually

adjusted backward and forward by turning the knob 70 exactly as in the constructions shown in Figs. 1 and 2.

The work on any transparent or translucent material is greatly facilitated by illumination of the transparent table top 4. Also, for the best results it is important that such illumination be as uniform and evenly distributed as possible. An important feature of this invention, therefore, resides in an improved apparatus for producing this result, and such apparatus is illustrated in Figs. 17 and 18. It comprises a trough-like reflector 98 which may conveniently be made of sheet metal, the reflector being of parabolic form in transverse section. It extends lengthwise of the table, or from right to left, Fig. 1. The upper margins of the reflector plates may be secured to the angular frame 54 in which the glass top 4 is mounted, while their lower edges are secured to the margins of a central supporting channel 99 extending the entire length of the reflector. In addition to the side plates 98-98 the reflector also includes end plates 100-100. A suitable source of illumination is mounted on the channel 99 consisting, for example, of incandescent electric lamps, or a lamp of the tubular type. In either event the source of light is elongated and is placed in the focal axis of the reflector 98 so that the rays of light issuing therefrom will be reflected upwardly in parallel relation to each other. In order to soften the glaring rays of light transmitted directly upward from the lamps, a translucent plate of opal or frosted glass 102 is positioned horizontally in the reflector structure directly over the line of lamps and is made of sufficient width to intercept all the glaring rays that otherwise would pass through the glass plate 4. It is, however, made sufficiently narrow so as to offer a minimum of interference with the reflected rays. This plate 102 may conveniently be supported in small brackets 103 secured to the end plates of the reflector. Also, one or more pedestals or rests, such as that shown in Fig. 17 at 104, may be used to support the plate 102 at intermediate points in its length. One of the side walls of the reflector also is provided with a door 105 hinged at 106 and releasably locked in its closed position, as by screws 107. This door affords convenient access to the interior of the reflector for the purpose of installing lamps, replacing them, or making other repairs.

The frame 5 for the table top preferably consists of two superposed sections *x* and *y*, Figs. 1, 10 and 19, of angular section, the side and end pieces of each frame being welded, riveted, or otherwise secured rigidly together, at their corners. Reinforcing corner brackets, one of which is shown in Fig. 10 at 108, are also secured in the four corners of the upper frame *x* to stiffen it. The racks on which the carriages run are secured to the horizontal flange of the upper section *x*. There is a tendency for these sections to warp, or in some cases to get out of proper angular relationship to each other during shipment or because of conditions peculiar to the location in which they are used. Faults of level may readily be corrected, but if the two lateral side members of the top frame are not exactly at right angles to the front and back members, then that fact will introduce errors in the work. This invention, therefore, provides a means operable to correct such errors of angular relationship.

Referring to Fig. 1 and also to Fig. 19 which shows a vertical section slightly in front of the

rearward frame members, it will be seen that small brackets 109-109 are secured rigidly to opposite ends of the lower frame section *y*. Each of them has an upwardly extending arm through which a set screw 110 is threaded and bears against the upper section. Consequently, if the upper frame section *x* is found to be out of square in a horizontal plane, it may be trued up by backing off the appropriate one of the two set screws just mentioned and tightening up the other. These two frame sections are connected together by two small plates 112-112 at the front of the table, as shown in Fig. 1, and at the back of the table by a similar plate 113, Fig. 19. The screws 114, by means of which this plate is secured to the upper frame member *x*, pass through slots in the plate 113. Before making the adjustment just described these screws should be loosened so as to allow the upper section to have more freedom of movement relatively to the lower section than otherwise would be permitted, and the screws should be tightened up after the adjustment has been completed. The lower frame *y* also is stiffened at the corners by gusset plates (not shown) but the two frames are not connected together except by the small plates 112 and 113 above referred to. This arrangement affords a very satisfactory means for correcting the angular errors above referred to.

The table provided by this invention represents an important advance over prior art constructions in accommodating a much wider range of work than these earlier constructions, and facilitating the operations performed on a table of this character to such a degree that the work is made easier and the amount of work which an operator can turn out in a given length of time is materially increased.

Having thus described our invention, what we desire to claim as new is:

1. A line-up table structure comprising the combination of a table top, two carriages mounted for movement across said top at right angles to each other, straight edges mounted on said carriages, and racks supporting said carriages for said movement, the racks for one of said carriages including sections supporting the carriage for movement into a level out of the plane of operation of the other carriage.

2. A line-up table structure comprising the combination of a table top, two carriages mounted for movement across said top at right angles to each other, straight edges mounted on said carriages, racks supporting said carriages for said movement, the racks for one of said carriages including portions supporting its respective carriage for movement into a position out of the path of operation of the other carriage, and means under the control of one of said carriages for locking the other in its inoperative position out of the way of the first carriage.

3. A line-up table structure comprising the combination of a table top, two carriages mounted for movement across said top at right angles to each other, straight edges mounted on said carriages, racks supporting said carriages for said movement, the racks for one of said carriages including portions supporting its respective carriage for movement into a position out of the path of operation of the other carriage, and automatic means for locking both of said carriages in their inoperative positions where each will be out of the way of the other.

4. A line-up table according to preceding claim

1, in which one of said carriages has a part bridging the other when the latter is in its operative position.

5. A line-up table structure comprising the combination of a table top, two carriages mounted for movement across said top at right angles to each other, straight edges mounted on said carriages, racks supporting said carriages for said movement, one of said carriages having gears meshing with its respective racks, and a spacing mechanism operable through one of said gears to give the carriage predetermined adjusting movements across said table, said mechanism being adjustable to change the extent of said movements.

6. A line-up table structure comprising the combination of a table top, two carriages mounted for movement across said top at right angles to each other, straight edges mounted on said carriages, racks supporting said carriages for said movement, one of said carriages having gears meshing with its respective racks, and a pawl and ratchet spacing mechanism operable through one of said gears to give the carriage predetermined adjusting movements across said table.

7. A line-up table structure comprising the combination of a table top, two carriages mounted for movement across said top at right angles to each other, straight edges mounted on said carriages, racks supporting said carriages for said movement, and a duplex spacing mechanism operable through one of said gears to give the carriage predetermined adjusting movements across said table, said spacing mechanism including a common operating element for both spacing units, and means operable to throw either unit of said mechanism into action selectively, as desired.

8. A line-up table structure comprising the combination of a table top, two carriages mounted for movement across said top at right angles to each other, straight edges mounted on said carriages, racks supporting said carriages for said movement, a duplex pawl and ratchet spacing mechanism operable through one of said gears to give the carriage predetermined adjusting movements across said table, said mechanism including a lever for operating both units of the spacing mechanism, means adjustable to limit the range of movement of the lever, and means operable to throw either unit into action to the exclusion of the other, as desired.

9. A line-up table structure comprising the combination of a table top, two carriages mounted for movement across said top at right angles to each other, straight edges mounted on said carriages, racks supporting said carriages for said movement, one of said carriages having gears meshing with its respective racks, a pawl and ratchet spacing mechanism operable through one of said gears to give the carriage predetermined adjusting movements across said table, means operable through said gear for manually adjusting said carriage independently of said spacing mechanism, and additional means operable to throw said spacing mechanism into and out of action at will.

10. A line-up table structure comprising the combination of a table top, two carriages mounted for movement across said top at right angles to each other, straight edges mounted on said carriages, racks supporting said carriages for said movement, one of said carriages having gears meshing with its respective racks, a pawl and

ratchet spacing mechanism operable through one of said gears to give the carriage predetermined adjusting movements across said table, means operable through said gear for manually adjusting said carriage independently of said spacing mechanism, and a clutch controlling the operative connection between said spacing mechanism and said gear.

11. A line-up table structure comprising the combination of a table top, two carriages mounted for movement across said top at right angles to each other, straight edges mounted on said carriages, racks supporting said carriages for said movement, one of said carriages having gears meshing with its respective racks, a spacing mechanism operable through one of said gears to give the carriage predetermined adjusting movements across said table, said mechanism including a manually operable lever for actuating the mechanism, a graduated scale cooperating with said lever to indicate its range of movement, and means adjustable to control said range of movement.

12. A line-up table structure comprising the combination of a table top, two carriages mounted for movement across said top at right angles to each other, straight edges mounted on said carriages, racks supporting said carriages for said movement, a duplex spacing mechanism operable through one of said gears to give the carriage predetermined adjusting movements across said table, said spacing mechanism including a common operating lever for both spacing units, means operable to throw either unit of said mechanism into action selectively, as desired, separate scales cooperating with said lever to designate adjustments produced by the respective units, and means adjustable to limit the range of movement of said lever.

13. A line-up table structure comprising the combination of a table top, two carriages mounted for movement across said top at right angles to each other, straight edges mounted on said carriages, racks supporting said carriages for said movement, one of said carriages including a truss bar, a straight edge associated therewith, said bar having a longitudinal groove in one edge thereof, a stop mounted on said bar and having a gib located in said groove, and means acting on said gib to lock the stop in its various adjusted positions on said bar.

14. A line-up table structure comprising the combination of a table top, two carriages mounted for movement across said top at right angles to each other, straight edges mounted on said carriages, said top including a frame, and means operable to adjust said frame angularly in substantially the plane of said top to correct errors of angular relationship of the side and end members of said frame to each other.

15. A line-up table structure comprising the combination of a table top, two carriages mounted for movement across said top at right angles to each other, straight edges mounted on said carriages, said top including a frame, racks supporting said carriages for said movement, and means operable to adjust the racks supporting one of said carriages to bring them into right angle relationship to the other racks.

16. A line-up table structure comprising the combination of a table top, two carriages mounted for movement across said top at right angles to each other, straight edges mounted on said carriages, racks supporting said carriages for said

movement, the top of said table including a frame comprising two sections mounted one above the other and both connected together at one end of the table, and means at the other end operable to adjust the latter end of one section in substantially its own plane relatively to the other section and without disturbing the vertical relationship of the two sections.

17. A line-up table structure comprising the combination of a table top, two carriages mounted for movement across said top at right angles to each other, straight edges mounted on said carriages, racks supporting said carriages for said movement, the racks for one of said carriages including portions supporting its respective carriage for movement into a position out of the path of operation of the other carriage, and automatic interlocking means for said carriages cooperating with them to prevent interference of one with the movements of the other.

18. A line-up table structure comprising the combination with a transparent table top, a straight edge, and means supporting said straight edge on said structure for movement across said top, of illuminating means for said top including a trough-like reflector of approximately parabolic form in transverse section positioned immediately below said top, an elongated source of light located substantially in the longitudinal focal axis of said reflector, and a translucent plate positioned longitudinally in said reflector immediately above said source of light and of such width as to intercept and soften the direct rays of light which originate at said source and travel through said transparent table top.
